UNITED STATES PATENT OFFICE.

HUBERT TAR'BUSH, OF LAKEWOOD, OHIO, ASSIGNOR OF ONE-HALF TO GEORGE ROBERT BARKER, OF LAKEWOOD, OHIO.

WRENCH.

1,244,172.

Specification of Letters Patent. Patented Oct. 23, 1917.

Application filed October 26, 1914. Serial No. 868,643.

To all whom it may concern:

Be it known that HUBERT TAR'BUSH, residing at Lakewood, in the county of Cuyahoga, State of Ohio, have invented new and 5 useful Improvements in Wrenches, of which the following is a specification.

My invention which will be hereinafter fully set forth and claimed relates to wrenches.

10 The object of my invention is a wrench having a movable clamping jaw that can be quickly adjusted and automatically tightened and locked; also a detachable pipe jaw for the same that can be readily placed or 15 removed and will retain its position when in use.

Figure 1 is a side elevation of my improved wrench, showing the clamping device in gear and the pipe jaw in position and 20 one part in section.

Fig. 2 is a bottom view of the same.

Fig. 3 is a partial top view, showing the pipe jaw.

Fig. 4 is a perspective view of the movable 25 clamping jaw.

Fig. 5 is a horizontal section on line 5—5, Fig. 1, showing the clamping jaw gear.

Fig. 6 is a transverse section on line 6—6, Fig. 1, in the direction of the arrow.

30 Fig. 7 is an end view, (shank end).

Fig. 8 is an end view of the adjusting screw, showing the sunk ratchet teeth.

Fig. 9 is a transverse section on line 9—9, Fig. 1.

35 Fig. 10 is a horizontal section on line 10—10, Figs. 1, 7 and 9.

Fig. 11 is a separate view, in perspective, of the locking device for the adjusting screw.

40 Fig. 12 is a perspective view of the detachable pipe jaw, and

Fig. 13 is a detail of the plunger in the pipe jaw.

The shank, A, carries the fixed jaw, B, as usual. The hand-end of the shank I prefer 45 to form with sunk panels on its sides as shown at α . The bottom edge of the shank, for a part of its length near the fixed jaw, is formed with beveled rack teeth, α' , made angular to conform with the thread of the 50 adjusting screw with which they will gear.

C, Figs. 1, 2, 4, 5, 6, 7, 9 and 10, is the movable clamping jaw, slotted as at 2, to receive

and slide on the shank A; it provides accommodation for the adjusting and clamping gear. For this purpose it is formed 55 with a gap 3 in its lower part, said gap having recesses 4 and 5 lengthening the same in its upper part for the reception of the adjusting screw and thus forming in its lower part two inwardly projecting shoulders, c and c' formed with recesses 6 and 7 for receiving and forming bearings for the pintles of the adjusting screw. The recess 6 is made wider near the face of the gap, to afford accommodation for a coil spring, 60 65 with a lateral slot, 6^a , to hold one end of said spring.

D, Figs. 1, 2, 5, 6 and 8, is the adjusting screw gearing with the rack teeth α' in the shank A and formed with pintles d and d^a , 70 the latter short and the former long, so as to pass through the coil spring, D¹. This spring has one end, d^a , bent and inserted into the screw body (at 8, Fig. 6) the other is held in the slot 6^a and tends to rotate the 75 screw in the direction of the arrow, Figs. 1 and 2, and throw it into gear with the rack. The screw formed with square threads, has them cut away on two sides, forming two 80 flat faces 9 and 10, adjacent to each other and forming a rectangular edge, 11, between them, one of the faces being fluted longitudinally to afford a better grip for the fingers. One end of the screw body, the one 85 having the short pintle d^a , has ratchet teeth 12, sunk into it, as shown in Fig. 8 and indicated in Figs. 1 and 10. These teeth are engaged by a dog, E, embedded and held 90 slidingly in the adjacent part of the movable jaw C and close to its bottom surface, as shown in Figs. 1, 2, 4, 7, 9, 10 and 11. It is provided with a lug, e, projecting below the lower surface of the part C and adapted to engage a check, 14, forming part of a slot 13 (Fig. 2) in said part C and being projected 95 by a spring, E¹, secured to a plug e^1 , in the end of the bore. Said plug forms part of a stem, e^2 , fitting the outer end of the slot 13 snugly; the plug being held in position by riveting or by a turn button, E³, as shown 100 in Figs. 1, 2, 5, 7, 9 and 10. The spring E¹ presses the dog into engagement with the ratchet 12 and its end engaging a transverse slot at the inner end of the dog, also imparts

to the latter a slight rotary movement, limited by the lug e and the slot and check 13 and 14. Upon turning the adjusting screw D against the tension of its actuating spring 5 D^1 , the incline of the teeth 12 rides against the incline of the locking dog E, forcing the latter backward against the pressure of the spring E^1 , which, by its turning force, turns the dog E on its longitudinal axis and causes 10 the lug e to engage in the pocket or check 14 of the slot 13, thus holding the dog back and preventing it from returning into engagement with the ratchet teeth 12, until said lug is released manually from its retaining 15 check 14. This device facilitates the use of the wrench in close quarters, when there may not be room for the hand to turn the screw.

A pin, a^2 , (Figs. 1, 2 and 7) is inserted in 20 the handle end of the shank A to prevent the movable jaw parting company with it.

F is the removable pipe jaw, shown in 25 Figs. 1, 2, 3 and 12. The solid operative part, f , has its back straight to fit the face of the fixed jaw B, its face f , beveled and serrated and made somewhat shorter than the length of the jaw B from the lower edge of the shank A to the tip, so that the square shoulder, f^2 , forming the top thereof, leaves 30 room between it and the lower edge of the shank A when the jaw is placed into position. Into this shoulder is inserted a shou- 35 dered movable pin, F^1 , the shoulder passing within the bore which forms its seat and the reduced part, surrounded by a coiled spring which tends to push the pin outward and cause it to act as a plunger im- 40 pinging on the lower surface of the shank A. From the shoulder f^2 , extends at each side to the head of the jaw B, a prong, f^3 , its back in line with the back of the part f , extended at a right angle, by an extension f^4 , over the head of the jaw and terminat- 45 ing in a hooked lug f^5 , so as to clip said head closely. The distance from the inner or contact edges of the arms f^4 to the shoul- 50 der f^2 is at least as much greater than the length of the hook lugs f^5 , so that the jaw F may be raised against the pressure of the plunger F^1 until the hooks f^5 clear the head of the fixed jaw, when the jaw F may be disengaged from its position on the fixed jaw.

While the movable jaw F is in its position 55 on the fixed jaw B, as shown in Figs. 1, 2 and 3, the plunger F^1 holds it there and forms an elastic seat which assists in relaxing the grip upon the pipe when it is desired to reverse the action or remove the 60 wrench.

The operation of the wrench does not require much further elucidation. The adjusting screw D is turned against the pressure of the spring D^1 until the plain face 9

faces the rack a^1 . The jaw C may then be 65 slid along the shank A in any direction and set against a nut or other object to be operated upon; the adjusting screw is then released and the spring D^1 will turn it back and throw the threads into gear with the 70 rack. The latter will allow the screw to turn until set close and lost motion is taken up and then hold it automatically.

The operation of the removable pipe jaw 75 needs no further explanation after what has been said in connection with the description of the same.

I claim as my invention:—

1. In a wrench, the combination of a shank having rack teeth, a fixed jaw on 80 one end of said shank, a movable jaw slotted to slide on said shank and having a gap in its lower part, said gap recessed in its upper part and having bearings for pintles in the faces of the lower part, a pintled ad- 85 justing screw journaled in said bearings and gearing into the rack on the shank and having the threads on two adjacent sides cut away to form flat faces at an approxi- 90 mately right angle to each other, a spring coiled upon one of the pintles of said screw with one end held in the enlarged pintle bearing and the other end bent and inserted in the end of the screw body and tending to throw the screw threads into gear with the 95 rack, ratchet teeth in the other end of the screw body, a dog embedded in and held slidingly in the lower part of the movable jaw, a lug on said dog projecting below the surface of the part in which it is em- 100 bedded and moving in a checked slot and a spring at one end of said dog pressing the same into engagement with said ratchet, substantially as set forth.

2. In a wrench having a rack-shank with 105 a fixed jaw in combination with a movable jaw having a gap, an adjusting screw pintled within the gap of said jaw, a spring on one of the pintles tending to turn the screw into gear with the rack on the shank, a 110 ratchet sunk in one end of the screw body, a dog slidingly embedded in said jaw oppo- 115 site said ratchet, a spring at the end of said dog pressing the same into engagement, a lug on said dog projecting beyond the sur- 120 face in which said dog is embedded and said surface being slotted and a check formed in said slot engaging said lug when the dog is retracted, substantially as set forth.

3. In a wrench, the combination of a 125 shank having rack teeth, a fixed jaw on one end of said shank, a removable serrated attachment resiliently mounted on said fixed jaw and adapted to have slight move- 130 ment along said fixed jaw, a movable jaw having a gap, an adjusting screw pintled within the gap of said jaw, a spring on one of said pintles tending to turn the screw

into gear with the rack, a ratchet sunk into one end of the screw body, a dog slidably embedded in said jaw opposite said ratchet, a spring at the end of said dog pressing the same into engagement, a lug on said dog projecting beyond the surface in which said dog is embedded, said surface being slotted and a check formed in such slot engaging

said lug when said dog is in its retracted position.

In testimony whereof I affix my signature, in presence of two subscribing witnesses.
